UNITED STATES PATENT OFFICE.

BENJAMIN WOLHAUPTER, OF NEW ROCHELLE, NEW YORK.

REMOVABLE WELDED RAIL-ANCHOR.

1,329,153.

Specification of Letters Patent. Patented Jan. 27, 1920.

Application filed October 28, 1918. Serial No. 259,989.

To all whom it may concern:

Be it known that I, BENJAMIN WOLHAUPTER, a citizen of the United States, residing at New Rochelle, in the county of 5 Westchester and State of New York, have invented certain new and useful Improvements in Removable Welded Rail-Anchors, of which the following is a specification.

This invention relates to an improvement 10 in welded rail anchors, and more particularly to a novel means of attaching an anchoring element to the rail by welds in a manner which admits of the ready removal of the anchor when it is desired.

15 The chief object of the invention is to utilize a welding operation for fastening a rail anchor to a rail while at the same time permitting the anchor to be removed intact without injury to the rail or to itself when 20 such operation is desired or required. In the attainment of this general object the invention has especially in view meeting the objections which are commonly urged against the use of welded rail anchors, such 25 for instance as the objection to the necessity of cutting away a permanently affixed anchoring element when the original track arrangement is disturbed with the danger of breaking the rail flange in the operation of 30 removing the anchor. Also, it is the purpose of the invention to provide a rail anchor structure involving a novel means of welding the same to the rail which facilitates the removal of the anchor without breakage or 35 injury to the anchor itself so that it is preserved intact for reapplication in a new location when track and ties are readjusted.

A further important object of the invention is to provide for welding the rail anchor or anchoring element to the rail in such 40 a manner that the points of weld are of comparatively small areas. This reduces to a minimum the danger of injury to the rail by the welding heat while at the same time 45 involving relatively small welded areas or spots each of which areas or spots is sufficiently weak or readily fracturable by a suitable tool or hammer blow, and yet in the aggregate are sufficiently strong to resist the 50 maximum strain or force imposed upon the anchor in the direction of the running of the rail.

Other objects of the invention are to provide an anchor fastening means generally 55 useful in connection with practically all forms of rail anchors or anchoring elements

which are to be fastened to the rail and cooperate with the tie, tie plate, spike or other fixed abutment. It is also the purpose of the invention to render the improved fastening 60 means especially available in connection with simple forms and types of anchoring elements such as rolled or stamped plates, one part of which is fastened to the rail and one part is presented for engagement with the fixed 65 abutment.

Accordingly, it is to be understood that a fundamental feature of the invention resides in the use of a particular form and arrangement of welded connection between a 70 rail anchor and a rail whereby the welded connection itself is readily fracturable to permit the removal of the anchor without injury to itself or to the rail while at the same time providing a sufficiently strong union between the anchor and the rail so that the anchor is capable of effectually resisting the maximum strain or force placed thereon in the direction of the running of the rail, thereby causing it to resist and prevent 75 creeping tendencies of the rail.

With these and other objects in view which will be readily apparent to those familiar with the art without further description it will be understood that the invention resides in the features above stated, broadly, and that the invention is susceptible of a wide range of application, and also capable of modification, several particular forms being shown in the accompanying 80 drawings, in which:—

Figure 1 is a perspective view of a simple angle plate type of anchor affixed to the edge of the rail flange in accordance with the present invention.

Fig. 2 is a perspective view illustrating another form of plate anchor fastened on top of the rail flange in accordance with the invention.

Figs. 3, 4 and 5 are similar fragmentary 100 views in plan illustrating simple plate anchors fastened to the rail flange in accordance with the invention, and coöperating with the spike or spikes as the abutments.

Fig. 6 is a perspective view illustrating another simple type of spike engaging anchor plate welded on the top of the rail flange in accordance with the invention.

Fig. 7 is a sectional plan view illustrating the application of the invention to that type 110 of rail anchor involving a mechanical movement of coöperating elements which in this

2 illustration are wedged upon the rail flange and engage with the tie.

Like reference characters designate corresponding parts throughout the several figures of the drawings.

As above pointed out the present invention involves fundamentally the feature of fastening a rail anchor or rail anchoring element to a rail by a plurality of welds or 10 welded connections each of which is sufficiently weak to be readily fracturable by a suitable tool or hammer blow, but which welds or welded connections in the aggregate are sufficiently strong to rigidly and 15 unyieldingly hold the anchor to the rail so that the anchor may have the capacity to resist the maximum strains imposed thereon by a running rail. At the same time each of these welds or welded connections occupies a relatively small area or spot so that there is only quite a small area of the rail metal heated and danger of injuring the rail metal by the welding operation is thereby 20 entirely eliminated or greatly minimized.

An exemplification of the invention as 25 above expressed is shown in Fig. 1 of the drawings, illustrating a simple angle plate type of rail anchor or anchoring element designated by the numeral 1. This type of anchor is shown arranged vertically alongside of the edge of the rail flange and depending below such flange, the upper edge of the said anchor being scarfed or beveled as at 2, to admit of the welded connections 3 being formed at points between the anchor and the edge of the rail flange. These welded connections may be made by any of the welding processes available for the purpose such for instance as by the oxy-acetylene 35 method, or by electric welding. It will also be understood that the present invention is available for use with any of the welding expedients such as welding the metal to metal whenever this is possible, or by the 40 use of separate welding metal to make scarf welds as shown in Fig. 1, or to make fillet welds as shown in the other figures of the drawings.

With further reference to the illustration 50 of Fig. 1 it will be understood, as already indicated, that the plural spaced welds 3—3 are intended to be fractured or broken away by a tool or otherwise when it is desired to remove the anchor intact for reapplication 55 or other purposes. In this form of the invention it will be noted that the anchor body is formed at one end with a bearing plate member 4 adapted to engage against the tie as an abutment.

A further view of the invention is given 60 by the illustration of Fig. 2 wherein an angle plate 5 overlies the rail flange and has a depending part 6 formed with a tie engaging plate 7. In this form of the invention 65 the part of the anchor overlying the rail

flange is fastened thereto by a plurality of spaced welded connections 8 having the same purpose and functions as the corresponding welded connections in all other forms of the invention.

Likewise, Figs. 3, 4 and 5 of the drawings, 70 illustrate other applications of the plural weld idea. For instance in Fig. 3 an anchor plate 9 is shown fastened to the edge of the rail flange by several relatively small 75 welded connections 10, of the fracturable type as already described, for the purpose indicated, and said plate 9 is provided with a notch 11 for engagement with the spike 12. In Figs. 4 and 5 an anchor plate 13 is shown 80 fastened by a number of small fracturable welds 14 to the top of the rail flange and projects beyond the edge of the rail flange having formed in its projecting part a notch 15 for engagement with the spike 16 as the 85 abutment element. And, in Fig. 5, the anchor plate 17 is fastened to the top of the rail flange by a number of small fracturable welds 18 and the projecting part 19 thereof engages at one side of the spike 20 90 or between two spikes 20—20.

Further, in Fig. 6 of the drawings an anchor plate 21 is shown fastened to the top of the rail flange by a plurality of small fracturable welds 22 and having a depending edge portion 23 overlapping the rail flange and notched as at 24 to engage a spike.

The fundamental idea of the invention is well exemplified by Fig. 7 of the drawings. In this figure is shown a type of rail anchor having a mechanical movement to place the same in gripping engagement with the rail flange. The type of anchor selected for this illustration is one having 100 separate movable gripping members 25 and 26 having a sliding interlocking wedge connection 27 therebetween and provided with flange gripping jaws 28 and 29 respectively which engage over the opposite rail flanges. 105 A tie bearing member 30 is carried by one of the members of this anchor. With this form of anchor, when the same has been applied to the rail flange and placed against the tie, the parts are tightly wedged together by a maul so that the jaws 28 and 29 become tightly and rigidly engaged with the rail flanges. Then the parts may be held firmly and unyieldingly in these positions by fastening the separate members of 110 the anchor to the rail flange by means of the plurality of small fracturable welded connections 31 having the same purposes and functions as the corresponding welded connections shown in the other figures of 115 the drawings. Obviously, to remove such an anchor as shown in the Fig. 7, it is only necessary to break or fracture the individual weak welds 31.

Other embodiments and other uses of the 120

invention will now be readily apparent without further description, and it will be understood that changes in the form, proportion, and minor details of construction 5 may be resorted to without departing from the spirit or sacrificing any of the advantages of the invention.

I claim:

1. A rail anchor having a relatively-weak 10 readily fracturable welded connection with the rail.
2. A rail anchor having a relatively weakened welded connection with the rail having its line of greatest strength and resistance 15 in the direction of the running of the rail.
3. A removable rail anchor having a plurality of welded connections with the rail to provide a relatively weakened welded fastening.
- 20 4. A removable rail anchor having a plurality of relatively small welded connections with the rail, each of which connections is relatively weak and readily fracturable.
- 25 5. A removable rail anchor having a plurality of welded connections with the rail, each of which connections is relatively weak and readily fracturable and in the aggregate

are of greater strength than the creeping force of the rail.

6. A removable rail anchor having a plurality of relatively small welded connections with the rail, each of which connections is relatively weak and readily fracturable but which in the aggregate are stronger than the creeping force of the rail. 30

7. A removable rail anchor having a plurality of relatively weak welded connections with the rail distributed in small areas or spots. 35

8. A removable rail anchor having a plurality of relatively weak welded connections with the rail distributed in small areas or spots and in the aggregate stronger than the creeping force of the rail. 40

9. A welded rail anchor having a detachable weld which is weaker than the adjacent parts of the rail and of the anchor. 45

In testimony whereof I hereunto affix my signature in the presence of two witnesses.

BENJAMIN WOLHAUPTER.
